US00D766245S

(12) **United States Design Patent** (10) **Patent No.:** **US D766,245 S**
(45) **Date of Patent:** **** Sep. 13, 2016**

(54) **IMAGING DEVICE**

- (71) **Applicant:** **Hewlett-Packard Development Company, L.P.**, Houston, TX (US)
- (72) **Inventors:** **Yu Ri Kim**, Singapore (SG); **Chung Chiet Edwin Chin**, Singapore (SG); **Shanthamallappa Kiran Kattesomanahalli**, Singapore (SG); **Nick Su**, Singapore (SG); **Yee Mei Cheng**, Singapore (SG); **Katherine Weilbacher**, Singapore (SG); **Qian Tao**, Singapore (SG); **Tee Kiang Phang**, Singapore (SG); **Wesley Chia**, Singapore (SG)
- (73) **Assignee:** **HEWLETT-PACKARD DEVELOPMENT COMPANY, L.P.**, Houston, TX (US)
- (**) **Term:** **15 Years**
- (21) **Appl. No.:** **29/545,638**
- (22) **Filed:** **Nov. 13, 2015**

Related U.S. Application Data

- (63) Continuation of application No. 29/480,993, filed on Jan. 31, 2014, now Pat. No. Des. 745,871.
- (51) **LOC (10) Cl.** **14-02**

CLAIM

(57) The ornamental design for an "imaging device," as shown and described.

DESCRIPTION

FIG. 1 is a front right perspective view of an imaging device. FIG. 2 is a front view of the imaging device of FIG. 1. FIG. 3 is a rear view of the imaging device of FIG. 1. FIG. 4 is a left side view of the imaging device of FIG. 1. FIG. 5 is a right side view of the imaging device of FIG. 1. FIG. 6 is a top view of the imaging device of FIG. 1. FIG. 7 is a bottom view of the imaging device of FIG. 1; and, FIG. 8 is a front left perspective view of the imaging device of FIG. 1.

Broken lines and unshaded portions contained within broken lines depict portions of the imaging device that form no part of the claimed design.

1 Claim, 8 Drawing Sheets
